E. B. Haywood.

By Attorneys,

UNITED STATES PATENT OFFICE.

EDMUND B. HAYWOOD, OF RALEIGH, NORTH CAROLINA.

KNIFE-SHARPENER.

1,083,490.

Specification of Letters Patent.

Patented Jan. 6, 1914.

Application filed April 4, 1913. Serial No. 758,869.

To all whom it may concern:

Be it known that I, EDMUND B. HAYWOOD, a citizen of the United States, residing at Raleigh, in the county of Wake, State of North Carolina, have invented certain new and useful Improvements in Knife-Sharpener; and I do hereby declare the following to be a full, clear, and exact description of the invention, such as will enable others skilled in the art to which it appertains to make and use the same.

This invention relates to improvements in sharpening devices, and particularly to devices for sharpening cutlery or other edged tools.

One object of the invention is to provide a simple device of this character by means of which a knife or the like may be passed therethrough to be effectively sharpened, and in which the pressure on the knife blade can be easily accomplished.

Other objects and advantages will be apparent from the following description when taken in connection with the accompanying drawings.

In the drawings: Figure 1 is a side elevation of the sharpener. Fig. 2 is a front elevation. Fig. 3 is a plan view. Fig. 4 is a vertical transverse section on the line 4—4 of Fig. 3. Fig. 5 is a vertical longitudinal section on the line 5—5 of Fig. 3. Fig. 6 is a vertical transverse section showing the knife in position to be sharpened.

Referring particularly to the accompanying drawings, 10 and 11 represent respectively the upper and lower blocks, these blocks being of suitable thickness and preferably rectangular in plan view. To the under face of the upper block 10 are secured the abrading elements 12, these elements being of any suitable material, as metal file, or stones. These abrading elements are secured in grooves 13 extending transversely of the under face of the block 10, and are arranged in suitably spaced parallel relation. Similar abrading elements 14 are secured in grooves 15 in the upper face of the lower block 11, and are in

parallel relation with each other, but in staggered relation to the elements of the block 10. The block 10 is formed with perforated ears 16 through which suitable fastening devices may be passed to attach the device to a support. Secured to the under face of the block 10, and adjacent the rear edge thereof is one end of a bow spring 17, the opposite end of said spring being secured to the upper face of the block 10. The spring 17 permits the blocks 10 and 11 to be yieldably adjusted toward and away from each other and pressure on the knife to be regulated.

In using the device, the knife blade is inserted between the free ends of the blocks and pressure applied on the upper block. The knife is then moved longitudinally between the blocks, the abrading elements beveling both sides of the edge of the knife at the same time. With the device it is only necessary to pass the knife back and forth between the blocks several times to produce a keen edge.

What is claimed is:

In a cutlery sharpening device, a block arranged for attachment to a support and provided with a plurality of transversely disposed parallel grooves in the upper face thereof, a second block disposed over the first block and in a normally inclined position with respect thereto, said second block being grooved in its underface, said grooves being arranged in staggered relation with respect to the grooves of the first block, abrading strips secured within the grooves of the block, the inner ends of the strips of the second block being normally disposed between the corresponding ends of the strips of the first block and a bow spring embracing the proximate portions of the blocks and secured thereto.

In testimony whereof, I affix my signature, in the presence of two witnesses.

EDMUND B. HAYWOOD.
